MOP WRINGER WITH PIVOTED SQUEEZE PLATE

George A. Chatel, Holyoke, Mass.

Application August 22, 1947, Serial No. 770,143

2 Claims. (Cl. 15—261)

1

My invention relates to improvements in mop wringers for use especially in wringing mops on the stairs.

The primary object of my invention is to provide a simply constructed, inexpensive mop wringer for use on a mop bucket to easily and quickly wring a mop, or the like, on stairs being cleaned, without subjecting the hands to the injurious effects of cleaning disinfectants, and/or other similar preparations commonly used in water for mopping purposes.

Other and subordinate objects, within the purview of my invention, together with the precise nature of my improvements will be readily understood when the succeeding description and claims are read with reference to the drawings accompanying and forming part of this specification.

In said drawings:

Figure 1 is a view in perspective illustrating my improved mop wringer attached to a mop bucket positioned on a stairs ready for use;

Figure 2 is a fragmentary view in vertical section;

Figure 3 is a view in rear elevation of the mop wringer detached;

Figure 4 is a view in plan;

Figure 5 is a view in perspective of the squeeze plate;

Figure 6 is a view in perspective of the rock shaft and crank disks thereon.

Referring to the drawings by numerals, my improved mop wringer, as shown, comprises, as its basic elements, a squeeze frame 1 for attachment, in a manner presently explained, to a mop bucket 2, and a squeeze plate 3 for cooperation with the squeeze frame 1 to wring a mop 4 as presently described.

The squeeze frame 1, which is preferably formed of light strong sheet metal, is vertically elongated and U-shaped in cross section with substantially parallel sides 5 and an upwardly and outwardly slanting flat front 6, said frame being open at its back. At the back of said frame 1, the vertical edges of the sides 5 are undercut, substantially midway of the top and bottom of said frame, to form a pair of vertical slots 7 in said sides 5 fitting downwardly over the rim 8 of the bucket 2, and said sides 5 are provided with leg portions 9 adapted to rest against the inner side of said bucket 2 so that said frame 1 may be suspended from the rim 8 partway in said bucket 2 and is overbalanced inwardly of said bucket 2 to maintain an upright position therein. When so suspended, the front 6 of said frame 1 extends downwardly into the bucket 2 to drain therein.

2

Slots 10 are formed in the front 6 of said frame 1, and similar slots 11 in the sides 5 to permit liquid squeezed from the mop 4 to drain quickly into said bucket 2.

5 The squeeze plate 3 fits between the sides 5 of the squeeze frame 1 loosely in upright position and is L-shaped in vertical section to provide a bottom lateral flange 12 extending toward the front 6 of said frame 1 at the bottom edge of said front 6 to support the mop 4 when the mop strands 13 are interposed between said front 6 and said plate 3. A pair of L-shaped reinforcing bars 14 extend vertically of the squeeze plate 3 at the back thereof adjacent opposite sides of said plate, and also extend under said flange 12.

A pair of upright links 15 are pivoted at lower ends thereof on a cross rod 16 connecting the lower ends of the legs 9, the upper ends of said links 15 being pivoted to the lower ends of the 20 reinforcing bars 14 by pivot pins 17 with cotter pins 18 therein, said links 15 providing for swinging adjustment of said squeeze plate 3 toward and from the front 6 of the squeeze frame 1. In this connection it is to be noted that the links 15 provide for said movement of said squeeze plate 3 toward the front 6 with the flange 12 below said front 6 so that the said flange will not interfere with movement of said plate 3 close to the front 6 of said frame.

25 For moving the squeeze plate 3, a transverse rock shaft 19 is rotatably mounted at its ends in the sides 5 back of the squeeze plate 3 and above the slots 7 to dispose the same above the mop bucket 2 and intermediate the top and bottom 35 of said plate 3, preferably below the transverse center of said plate. A handle socket 20 of metal is provided to fit on one squared end 21 of the rock shaft 19 in upstanding position with the lower end of a wooden handle shaft 22 fitted 40 therein. A pair of crank disks 23 are suitably fixed eccentrically on the rock shaft 19 adjacent opposite sides 5 of the squeeze frame 1 and between said sides. A pair of links 24 are pivoted at one end, as at 25, on said disks 23, eccentrically of the rock shaft 19, to extend forwardly over said rock shaft with the other ends thereof pivoted as at 26, to the reinforcing bars 14.

The mop bucket 2 with which my improved mop wringer is specially designed to be used is 50 of a semi-cylindrical type in cross section with a flat side 27 to which said wringer is attached, as described, such a bucket being well adapted for standing on the tread 28 of a stairs with the flat side 27 facing the riser 29 and fitting against the front edge of the next higher tread. When thus

positioned, such a bucket 2 is more stable than the usual round bucket and thereby lends stability to the mop wringer.

The manner in which the described mop wringer is operated will be readily understood. By swinging the handle shaft 22 rearwardly until the links 24 rest on the rock shaft 19, the squeeze plate 3 may be moved rearwardly away from the front 6 of the squeeze frame 1 to open up the mop wringer. The strands 13 of the mop 4 may then be inserted downwardly between the squeeze plate 3 and said front 6 on the flange 12, and the handle shaft 22 then pulled forwardly thus rocking the rock shaft 19 and revolving the crank disks 23 so as to thrust the links 24 forwardly and thereby move the squeeze plate 3 toward the front 6, as shown by dotted lines in Figure 2, whereby the strands 13 will be squeezed between said squeeze plate 3 and said front 6 to wring the mop. In this connection, it is to be noted that the links 15 and 24 provide for downward movement of the squeeze plate 3 during its forward movement whereby said plate 3 exerts a downward squeezing action against the mop strands 13 which facilitate wringing said strands. During the described wringing operation, the bucket 2 may be steadied by the hand, or not, as occasion may require.

The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claims.

Having described the invention, what is claimed as new is:

1. A mop wringer for attachment to the rim of a bucket comprising a frame including an open back and a closed front, and sides adapted to fit downwardly over said rim to support said frame on the rim with said front in upright position, a squeeze plate in said frame in upright position

at the back thereof for movement toward said front to squeeze a mop therebetween, links pivoted to said sides and to the lower end of said plate for supporting said plate and causing the same to move downwardly during movement of said plate toward said front to thereby exert a downward squeezing action against said mop, a swingable handle on said frame, and means operative by said handle to move said plate toward said front.

2. A mop wringer for attachment to the rim of a bucket comprising a frame including an open back and a closed front, and sides adapted to fit downwardly over said rim to support said frame on the rim with said front in upright position, a squeeze plate in said frame in upright position at the back thereof for movement toward said front from a normal position to squeeze a mop therebetween, links pivoted to said sides and to the lower end of said plate for supporting said plate and causing the same to move downwardly during movement of said plate toward said front to thereby exert a downward squeezing action against said mop, a handle swingable on said frame from a normal position, and means operative by said handle to move said plate toward said front comprising a rock shaft, crank disks on said shaft, and links connecting said disks to said plate and overlying and engaging said shaft in the normal position of said plate and handle to establish said position.

GEORGE A. CHATEL.
